UNITED STATES PATENT OFFICE.

WILLIAM G. LATIMER, OF DETROIT, MICHIGAN, ASSIGNOR TO THE LATIMER
CASH REGISTER COMPANY, OF SAME PLACE.

CASH-REGISTER.

SPECIFICATION forming part of Letters Patent No. 451,493, dated May 5, 1891.

Application filed May 26, 1890. Serial No. 353,132. (No model.)

To all whom it may concern:

Be it known that I, WILLIAM G. LATIMER, a citizen of the United States, residing at Detroit, in the county of Wayne and State of Michigan, have invented certain new and useful Improvements in Cash-Registers, of which the following is a specification, reference being had therein to the accompanying drawings.

10 This invention relates to new and useful improvements in indicating mechanism for cash-registers; and the invention consists in the peculiar construction of such mechanism, consisting of dials actuated through levers which are operated by the keys; further, in the peculiar construction of the mechanism for holding the operated dials in their adjusted position; further, in the peculiar construction, arrangement, and combination of 20 the various parts, all as more fully herein-after described.

In the drawings, Figure 1 is a rear elevation of my indicating mechanism applied to a cash-register. Fig. 2 is a horizontal section 25 on line $\alpha\alpha$ in Fig. 1. Fig. 3 is a vertical section on line $\gamma\gamma$ in Fig. 1. Fig. 4 is a front elevation of the dials.

The device herein described is intended as an improvement upon my patent, No. 409,107, 30 dated August 13, 1889. The machine belongs to that class in which the indication is effected by arranging two or more banks or groups of nine keys, the keys of each group being numbered from 1 to 9, respectively. Each 35 group represents a monetary denomination, units, tens, and hundreds. The depression of each key presents to view a number of corresponding value to that key, and the grouping of the figures exposed by the depression 40 of a key in each group gives the total amount of the indication. This has usually been accomplished by arranging a separate tablet upon a rod carried by each key. My invention consists in substituting for these tablets 45 a single disk for each group of keys, said disk having the numerals and a cipher thereon.

A is the casing or frame of the machine, in which are journaled the key-levers B upon the shaft C.

50 D are the indicator-rods, and D' are the register-actuating rods, (the registering mech-

anism not being shown,) all of these rods being supported in suitable guides E. The rods D are preferably round, and to prevent their turning on their axis a guide-arm a is attached to their front side, projecting between the register-actuating rods and guided thereby, the register-actuating rods being secured at the side of the key-levers, while the indicator-rods rest centrally upon the key-levers. 60

The indicator-rods at their upper ends carry the rearwardly-projecting pins b, adapted to bear against the disk-levers, of which there are three c c' c'', one for each group. The levers c c' of the units and hundreds groups 65 are pivoted upon a common pin s centrally of the machine, and the lever c'' for the middle group is journaled upon the pin s' at one side of the machine. These levers each carry a segmental rack-bar d d' d''. The rack-bar 70 d meshes with the pinion c upon the shaft of the disk f; the rack-bar d' meshes with the pinion c' upon the shaft of the disk f', and the rack-bar d'' meshes with the pinion c'' upon the shaft of the disk f''. These 75 disks are each numbered upon their front face near the periphery with the numerals and a cipher so arranged that the cipher upon each disk is normally exposed to view through a suitable aperture in the front of 80 the casing, the disk-levers so constructed as to be differently moved by each indicator-rod. This I preferably accomplish by forming a series of bearings g upon the lower side of the lever, each bearing being arranged in 85 such relation to the pins b upon the indicator-rods that sufficient motion will be imparted to the disk through the rack-bar to bring the number corresponding to the number upon the operated key opposite the aperture in the casing. The same result may be obtained by making the lever flat and arranging the pins at different heights upon the rods. This being simply an obvious modification, it is not herein shown. This construction 90 enables me to group my keys properly from 1 on the right to 9 on the left, and to arrange the numbers progressively upon the disk, as shown in Fig. 4.

The mechanism for holding up the indicator-rods and allowing those previously operated to drop may be of any suitable con- 100

struction, but I preferably use that shown in the drawings, consisting of the pivoted cross-bars *h*, one for each group of keys connected together by the pins *i*, which bear against the stops *j* to hold the bar in its normal position, as shown in Fig. 3.

k are pins, one upon the rear side of each of the indicator-rods and adapted to rest upon the top of the bar *h* in their elevated position.

l is a cross-bar extending across all the keys of the machine and supported by means of the hanger *m*. This bar carries the vertical supporting-rods *n*, upon which is pivotally secured the striker-arm *o*, adapted to move the bar *p* horizontally, said bar being held in position by means of the links *q q'*. The link *q'* has the upwardly-extended arm *r*, which strikes the arm *r'*, connected to the bar *h* to turn the bar upon its pivot in such a manner as to disengage it from the pin *k* and allow the operated tablet-rod to drop.

The parts being thus constructed, their operation is as follows: The disks being in their normal position with all of the ciphers exposed, should the operator desire to indicate \$7.60, (the amount shown in Fig. 4,) he does so by depressing the 6-key in the tens group, carrying up its indicator-rod. The first movement of the key will withdraw the bar *h* from the rear side of the indicator-rods through the mechanism described, which will allow any previously-operated keys to drop. As soon as the striker-arm *o* has passed the bar *p* said bar will return to its normal position by gravity, allowing the bar *h* to again assume its normal position. (Shown in Fig. 3.) In the continued upward movement of the indicator-rod the pin *k* will turn the bar *h* upon its pivot until the pin has passed, when the bar will drop back again and prevent the descent of the indicator-rod. In the upward movement of the pin *b* upon the indicator-rod it will strike its bearing upon the disk-levers, raising said levers until the key has finished its stroke, rotating the disk through the medium of the rack-bar *d* until the 6 is exposed to view. Upon releasing the key the key-lever will return to its normal position, but the rod will remain in its elevated position by the pin *k* resting upon the bar *h*. The 7-key having been simultaneously struck, it also will be held up (the dollars-disk having been rotated in the manner described) until the 7 is exposed through the aperture. With this number exposed, it having been also registered by any suitable registering mechanism, if the operator next desired to indicate a one-dollar sale he would strike the 1 in the dollar group. The lever *c'* will be held up by the 7-indicator-rod previously struck until it is released by the withdrawal of the bar *h*, when it will fall by gravity and bear upon

the rising pin *b* of the rod operated by the 1-key, the old indication being effaced and the new indication being effected in the manner described. It will thus be seen that by having a single flat disk for each group I am enabled to effect the indication in a most simple manner and with very simple mechanism. By this construction it will be seen that the operating-lever and the indicating-disk are both moved proportionate to the value of the key struck. It will also be seen that if two keys are simultaneously struck only the figure representing the key of highest value will be exposed to view. Thus all necessity of having mechanism to prevent the simultaneous operation of two keys is obviated. The disk is rotated toward normal by the weight of the operating mechanism bringing down the operating-lever and through the medium of the segmental gear and the gear-wheel.

I claim—

1. In a cash-register, the combination, with the frame, of three disks having digits thereon mounted in the frame, two in line and one in the rear and between the others, gears on said disks, levers having segmental racks thereon engaging with the gears and stepped lower edges, and a series of operating-keys arranged to engage the stepped portion of the levers, substantially as described.

2. In a cash-register, the combination, with a series of rotary disks having digits on their faces, of a series of stepped levers having racks thereon, gears connected with the disks engaging the racks, and keys for actuating the levers, substantially as described.

3. In a cash-indicator, the combination, with a series of rotary disks having digits thereon, of gears on the shafts of the disks, two levers fulcrumed on a common shaft and formed with segmental racks for engaging the gears on the disks, and a lever fulcrumed at a point remote from the other fulcrum and having a segmental gear engaging the gear on a disk, the inner edge of the lever being formed with a series of strips and keys for engaging with the levers, substantially as described.

4. In a cash-indicator, the combination, with the frame, of a series of disks having digit signs on their front faces, a series of levers having stepped lower edges and segmental racks, gears on the disks, indicating-rods, horizontal pins on the upper ends of the rods, and keys for moving the rods, substantially as described.

In testimony whereof I affix my signature in presence of two witnesses.

WILLIAM G. LATIMER.
